L. B. VICTOR

VERNIER PLATE CONDENSER

Filed May 14, 1924

INVENTOR

INVENTION
Leonard B. Victor
BY
Percy Freeman
ATTORNEY

UNITED STATES PATENT OFFICE.

LEONARD B. VICTOR, OF NEW YORK, N. Y.

VERNIER PLATE CONDENSER.

Application filed May 14, 1924. Serial No. 713,220.

This invention relates to improvements in electrical condensers, particularly to types used in connection with radio reception and transmission apparatus in which high potential electric currents are employed.

One of the objects of the invention is to provide a simple and efficient condenser, the capacity of which may be varied in an unusual but practical manner and in which 10 the most minute adjustment is easily attained.

Another purpose is to produce a condenser in which a plurality of stator and rotor plate units are adjusted into an approximately proper position by manipulation of a dial, final accuracy being obtained by an independent entity, co-operative with said units and actuated on the micrometer screw principle.

20 A further aim is in the provision of an exceedingly sensitive instrument capable of acting up to the full capacity of the plate surfaces used, occupying a minimum of space and relatively inexpensive to construct.

These and other aims and objects, such as simplicity of action, non-liability of failure by disarrangement, compactness and general utility, are accomplished by the novel 30 construction, combination and arrangement of parts hereinafter described and shown in the annexed drawing, forming part of this disclosure, and in which:—

Figure 1 is a partial side elevational partial vertical sectional view of an embodiment of the invention, the section being taken substantially on line 1—1 of Figure 2.

Figure 2 is a rear view of the same, parts 40 being broken away to show the construction.

Figure 3 is a bottom plan view thereof.

The apparatus, as shown in the drawings, is attached to a dielectric panel or plate 10 45 as ordinarily used in such structures, and consists of a pair of metal plates 11 and 12, respectively front and rear and constituting a frame held rigidly to the panel 10 by screws 13 and 13' in threaded engagement 50 with a nut 14 acting as spacers between the plate 11 and panel 10.

On the inner adjacent sides of the plates 11 and 12, at their upper edges and central of the same, are bosses 15 and 16 into

which are screwed adjustable bushings 17 55 and 18, held when in adjustment by clamp nuts 19 and 20.

A spindle 21 is rotatably mounted in these bushings, one of its extending ends 22 projecting through an opening in the panel 10 60 and having fixed on it a dial 23 provided with a twirling knob 24.

The central portion 25 of the spindle is preferably enlarged and square in cross section, its ends blending by curves into the 65 cylindrical portions and are adapted to make contact with the inner ends of the bushings 17 and 18 so as to be adjusted longitudinally in the frame thereby, and so as to adjust the amount of friction between the spindle and 70 the bushings.

Fixed in spaced relation on the square element 25 are a plurality of sector shaped, flat plates or rotors 26, the same being arranged in register and with relation to the 75 dial 23.

The fixed plates or stators 27 arranged intervening the rotors, presenting like profiles and in addition are formed with oppositely extending arms 27' which are fixed 80 on rectangular conductor bars 28 fixed at their ends in insulators 29, as rubber or like, and held firmly between the plates 11 and 12 by rivets 30 or like fastenings.

Thus far, the description is not unlike 85 that of ordinary apparatus for the same purpose, that invention residing in the added features, now following.

A binding post 31, being insulated from the plate 12 by insulator 29, is attached to 90 and in electrical engagement with one of the bars 28, and another binding post 32 conducts current to the plate 12 and thence to the rotors 29.

On the lower, outer side of the plate 12, 95 at the center thereof, is a boss 33, drilled and screwthreaded from its inner side and receptive of a threaded stem 34 formed on a spindle 35, revoluble in the opposite plate 11 and extending through an opening 100 in the panel 10, its outer end being provided with a twirling knob 36.

Fixed on the spindle 35 between the plates 11 and 12 is a sleeve 37, against which, clamped by the collar 38, is a plate 39 extending coincident with the outer area of the rotors 26 and backed by a relatively narrow plate 40 acting as a re-enforcement,

These plates 39 and 40 are slidably engaged on guide pins 41 fixed in the plate 12 to extend inwardly and out of the path of action of the rotor plates.

5 It will now be obvious that the rotors 26 may be moved laterally within the casing relative to the fixed stators 27, by adjusting the bushings 17 and 18 and that they may be rotated by turning the dial 23 so as to 10 increase or decrease the relative superficial areas in the usual manner, thus performing the usual function of a condenser in obtaining desired results.

It will be further apparent that when such 15 adjustment has been made, that it is readily possible to make a fine and final adjustment by actuating the knob 36, causing the screw to move in the boss 33, and actuating the plate 39 towards or from the outermost 20 stator plate, giving, in effect, a micrometer adjustment and always presenting a desirable air gap or space therebetween.

As changes of construction could be made 25 within the scope of the invention, it is intended that all matter contained in the foregoing description or shown in the accompanying drawings shall be interpreted as illustrative and not in a limiting sense.

Having thus described my invention, what 30 I claim as new and desire to secure by Letters Patents, is:—

1. A condenser comprising in combination 35 with a frame, a plurality of stator plates and rotor plates intervening, a spindle having threaded connection in said frame, and an independent vernier plate engaged with

said spindle and movable in said frame toward or away from the other plates.

2. A condenser comprising in combination with a frame, a plurality of stator plates 40 and rotor plates intervening, a spindle having threaded connection with said frame, and an independent vernier plate engaged with said spindle and movable in said frame toward and away from said other plates, 45 and means for rotating said spindle.

3. In a condenser the combination with a pair of end plates, a plurality of stator plates and rotor plates intervening, of a 50 spindle having threaded connection in one of said end plates, an independent vernier plate, pins set in one of said end plates for guiding said vernier plate, said plate being moved by said spindle.

4. In a condenser the combination with 55 a pair of end plates, a plurality of stator plates and rotor plates intervening, of a spindle having threaded connection in one 60 of said end plates, an independent vernier plate movable toward and away from said stator plates, the latter being insulated from the rotor plates, and the rotor plates and end plates being in electrical contact, means for adjusting said rotor plates relative to the fixed stator plates, and means for adjusting 65 said independent vernier plate relative to said stator plates.

Signed at New York, in the county of New York and State of New York this 17th day of April 1924.

LEONARD B. VICTOR.
